UNITED STATES PATENT OFFICE.

JOSEPH ZIMMS, OF LONG ISLAND CITY, NEW YORK.

BUSHING-PULLER.

No. 867,181.

Specification of Letters Patent.

Patented Sept. 24, 1907.

Application filed June 25, 1907. Serial No. 380,748.

To all whom it may concern:

Be it known that I, JOSEPH ZIMMS, a citizen of the United States, and a resident of Blissville, Long Island City, county of Queens, State of New York, 5 have invented certain new and useful Improvements in Bushing-Pullers, of which the following is a specification.

This invention relates to bushing pullers and is intended to provide an improved device for extracting 10 bushings and is more especially adapted for the withdrawing of bushings from the chucks of rock drill pistons.

Owing to the pressure exerted in forcing a new bushing into a piston and the constant pounding which the 15 bushing receives during the operation of the rock drill, the bushing, when worn, is so tightly forced into the piston that it can only be extracted with great difficulty. The object of the invention is to provide an improved device by means of which the bushings may 20 be extracted in a quick and reliable manner, and without injury to the pistons.

For this purpose my invention consists of a bushing puller, comprising a central rod, having a recess near one end and a slot near the other, a key for the recess 25 projecting beyond the face of the rod, a sleeve, and a wedge interposed between one end of the slot of the rod and the sleeve.

The invention consists of certain further novel features and combination of parts which will be more 30 fully described hereinafter and finally pointed out in the claims.

In the accompanying drawings Figure 1 represents an elevation of my improved bushing puller intended more particularly to show the different sized recesses 35 of the sleeve, Fig. 2 represents a longitudinal section, showing the bushing puller as inserted into a piston, ready to be operated for the withdrawal of the bushing, Fig. 3 shows a vertical transverse section, taken on line 3—3 of Fig. 2, Fig. 4 represents an end 40 view of the sleeve, and Fig. 5 shows a perspective view of the key.

Similar letters of reference indicate corresponding parts.

Referring to the drawings A represents a central rod, 45 having one portion thereof of smaller diameter than the other, whereby at the juncture of the two portions a shoulder a is formed. The portion of smaller diameter, a^1 , is provided with a recess B, located approximately below the usual opening C¹ of the bushing C, when the 50 rod A is inserted therein. The portion of the rod of larger diameter, a^2 , is provided with a slot M, having one side thereof inclined to the axis of the rod, and the side opposite perpendicular thereto. This slot is adapted to be engaged by a wedge N. A sleeve O 55 concentric to the rod is provided with a plurality of recesses of different sizes, a small size, o^1 , an inter-

mediate size, o^2 , and a large size, o^3 . The number and size of the recesses may be changed as required.

A key G having a plane bottom, one end curved, with a shoulder portion g at that end, and the other end inclined as respects the bottom, is adapted to be inserted into the recess B, so that the inclined end of the key engages the inclined end of the recess. As is usual, the opening of the bushing is located below the opening D of the chuck E of the piston rod E¹. 60

The operation of my improved puller is as follows:

After the drill has been removed from the chuck of the piston, which still retains the jammed-in bushing, the end a^1 of the rod A is inserted into the bushing C, until the shoulder of the rod abuts against the end of the bushing C. 70

The recessed end of the rod, a^1 , is inserted into the bushing, so as to have its recess B directly below the opening C¹ of the bushing C and the opening D of the chuck E. The sleeve O is then moved along the

larger end of the rod A until it abuts against the end of the chuck E of the piston rod, after which the wedge N is inserted into the slot M of the rod A, and the sleeve 75

so turned as to have its largest recess, o^3 , engaged by the wedge. The wedge N is then given a sudden blow, whereby the rod A will be caused to be moved out- 80

wardly from the bushing, and by reason of the key having its curved upper end projecting beyond the surface of the rod, and this projecting end engaging the bushing C, the latter will have the sudden blow or blows imparted to the wedge, transmitted to it, whereby it will be 85

loosened from its jammed-in position. Further blows imparted to the wedge will cause the rod to be moved outwardly and the bushing to be drawn along with it. At the end of the effective movement of the wedge N, 90

it is withdrawn, the sleeve O rotated so as to bring the next smaller sized recess, o^2 , in line with the wedge. Force is then applied to the wedge and thus the rod A further withdrawn and the bushing thereby further extracted. At the end of its effective stroke the wedge 95

is again withdrawn, the sleeve O rotated, and the wedge caused to engage another recess, now the smallest, o^1 . Force is again applied to the wedge, having the same 100

result as before, at the end of which the bushing is entirely extracted, with no injury to the chuck of the piston.

My improved bushing puller has been described as applicable more particularly to the extraction of bushings from chucks of rock drill pistons. It is clear that such puller may be applied to the extraction of bushings of similar and other devices.

I have described one particular embodiment of my invention and modifications thereof may be made without departing from the spirit of my invention.

Having thus described my invention, I claim as new and desire to secure by Letters Patent:

1. A bushing puller, comprising a central rod having a recess near one end and a slot near the other, a key for

the recess projecting beyond the face of the rod, a sleeve, and a wedge interposed between one end of the slot of the rod and the sleeve.

2. A bushing puller, comprising a central rod provided with a slot near one end and a recess near the other, having an inclined portion at one end thereof, a key having an inclined end adapted to engage the inclined portion of the recess, a sleeve, and a wedge interposed between one end of the slot of the rod and the sleeve.

10 3. A bushing puller, comprising a central rod having a recess near one end and a slot near the other, a key for the recess projecting beyond the face of the rod, a sleeve having a plurality of recesses at one end of different sizes, and a wedge adapted to engage some of the recesses of the 15 sleeve, and the slot.

4. A bushing puller, comprising a central rod provided with a recess near one end and a slot near the other, said recess having a plane bottom with an inclined portion in respect thereto at one end thereof, and a curved portion 20 at the other end, a key having a curved portion at one end and an inclined portion at the other adapted to respectively engage the corresponding portions of the recess of the rod, a sleeve, and a wedge interposed between one end of the slot of the rod and the sleeve.

25 5. A bushing puller comprising a rod having means whereby it may be engaged with the bushing, a sleeve embracing the rod, and a non-rotatable wedge whereby the rod is displaced relatively to the sleeve.

6. A bushing puller comprising a rod having means 30 whereby it may be engaged with the bushing, said rod be-

ing provided at the opposite end with a slot, a sleeve to embrace said rod, and a wedge in said slot whereby the rod is moved relatively to said sleeve.

7. In a bushing puller, the combination, with a bushing-pulling rod having a slot therein, of a wedge in said slot, 35 and a device rotatable about the rod and having a plurality of wedge-receiving openings.

8. In a bushing puller, the combination, with the rod having a slot, and the wedge operating in said slot, of a device mounted to turn on the rod and intended to be interposed between the wedge and the chuck, said device causing the rod to be driven outwardly through different distances according to the angular position of said device. 40

9. In a bushing puller, the combination, with the rod having a slot therein, and the wedge operating in said 45 slot, of a sleeve mounted to turn on said rod between the wedge and the chuck and provided with wedge-receiving openings of different sizes.

10. In a bushing puller, a rod to withdraw the bushing having a recess provided with an inclined end-portion, and 50 a key seated in said recess and having an inclined end to engage said inclined portion, said key having a shoulder to engage in the slot in the bushing.

In testimony, that I claim the foregoing as my invention, I have signed my name in presence of two subscribing witnesses. 55

JOSEPH ZIMMS.
